UNITED STATES PATENT OFFICE.

JAMES W. MOORE, OF MOULTRIEVILLE, SOUTH CAROLINA.

LOCKED HOUSING FOR VALVES.

Application filed September 9, 1922. Serial No. 587,161.

To all whom it may concern:

Be it known that I, JAMES W. MOORE, a citizen of the United States, residing at Moultrieville, in the county of Charleston and State of South Carolina, have invented certain new and useful Improvements in Locked Housings for Valves, of which the following is a specification, reference being had to the accompanying drawings.

10 It is the purpose of the present invention to provide a device of this kind applicable on pipe lines (through which any fluid may pass) in general use, either under or above ground, or indoors or outdoors, in fact regardless of where the pipe line may be located, for the purpose of housing various valves, spigots, or the like to prevent tampering therewith by unauthorized persons, especially when valves are located in public places.

Another purpose is to provide a housing including a lock, which may house the entire valve, or may house the hand wheel of the valve, the housing to be engaged with the valve casing immediately below the stuffing box, thereby preventing access to the wheel, and also preventing the valve from being tampered with. Obviously the locked housing may be constructed any size, for housing any size of valve casing or hand wheel.

Still another purpose is to provide a locked housing constructed of any suitable sheet metal, preferable thin sheet steel, light but necessarily strong, durable and rigid, the housing in the present instance comprising a base section and two hingedly supported sections, the base section to engage under the valve, while the two hingedly supported sections may swing toward each other and over the valve casing, so that in connection with locking means, tampering with the valve or any part thereof by unauthorized persons may be prevented.

45 A further purpose is the provision of a device of this character, wherein the two hingedly supported sections are each constructed of a single piece of sheet metal, preferably thin sheet steel, formed so as to provide three sides and a top end, one of the sides having extension flanges overlying and secured to the other sides to form the section, said flanges being extended at one end of the section, for the purpose of pivotally riveting the section on the base section. When the sections are opened, they

may assume approximately a 45° angle with relation to the base section, to permit access to the valve.

It is to be understood that the particulars herein given are in no way limitative and that while still keeping within the scope of the invention, any desired modifications of detail and desired proportions may be made in the apparatus according to circumstances.

The invention comprises further features and combination of parts, as will be hereinafter set forth, shown in the drawings and claimed.

In the drawings:—

Figure 1 is a view in perspective showing the locked housing for housing an entire valve;

Figure 2 is a sectional view on line 2—2 of Figure 1, showing the two hingedly supported sections open in dotted lines;

Figure 3 is a sectional view on line 3—3 of Figure 1 at right angles to Figure 2, showing the pipe line and valve in side elevation;

Figure 4 is a perspective view of the locked housing.

Figure 5 is a sectional view on line 5—5 of Figure 4;

Figure 6 is a horizontal sectional view on line 6—6 of Figure 4;

Figure 7 is a perspective view of the locked housing detached from the valve, and showing the two hingedly supported sections open;

Figure 8 is a detail view of the blank from which one of the hingedly supported sections is constructed, showing the parts of the blank partly bent;

Figure 9 is a detail view of the blank from which the base section is constructed, showing certain parts thereof bent to form the section;

Referring to the drawings, 1 designates the pipe line, through which any suitable fluid may pass. This pipe line may be under or over ground, or indoors or outdoors, or any other suitable location.

Carried by the pipe line is a conventional form of gate valve 2, which carries the usual hand wheel 3, for operating the valve proper (not shown).

The locked housing comprises a base section 4 and the two hingedly supported sections 5. The base sections comprises a bottom 6 the sides and ends 7 and 8 integrally

connected to the bottom, and carried integrally by the side pieces are flaps 9, which overlie and are riveted or otherwise secured at 10 to the end pieces of the base section.

The end pieces 8 have semi-circular openings 11, which engage the pipe line.

Each hingedly supported section comprises a main broad side 12, the two relatively narrow sides 13 and the top end piece 14. The relatively narrow sides 13 are formed integrally with the top end piece.

The broad side is provided with opposed flanges 15, certain ends of which are pivotally mounted on the end pieces 8 of the base section, by means of suitable rivets 16, whereby the hingedly supported section may be mounted on the base section, so as to swing over the valve casing or laterally to assume a position at a 45° angle to the base section.

As previously stated the sides 13 are integral with the top end piece, therefore when the top end piece is bent, to assume a position at right angles to the broad side, the side pieces 13 are bent to assume parallelism with each other, and while so disposed the flanges 15 are bent to overlie the side pieces 13 and are riveted, spot welded, brazed or otherwise fastened thereto, so as to insure a rigid and secure housing section, for protecting and locking the valve against being tampered with by unauthorized persons.

The lower corners of the adjacent edges of the side pieces 13 of the hingedly supported sections are cut away, causing to be formed quarter circular portions, which engage with the pipe line, and when the two hingedly supported sections are closed the quarter circular portions and the semi-circular openings cause circular openings to be formed in the housing for the reception of the pipe line, as shown in Figure 1.

In Figures 1, 2 and 3 the two hingedly supported sections are provided with a padlock 17, for the purpose of locking the two sections together, thereby preventing access to the valve or the handle wheel.

However in certain other figures where the complete housing is illustrated, a suitable spring lock is employed, as indicated at 18, which will lock when the two sides are pressed together. It may be that the spring lock is more essential and more useful than the padlock, as the parts lock quicker and with less trouble than with the padlock, since a person would not be required to place the hasp over a keeper, as when a padlock is used.

In certain of the figures where the housing is shown as applied to a valve to merely house the hand wheel it will be noted that the circular opening in one side of the hous-

ing is formed around the casing of the valve, at a point immediately below the stuffing box, for the purpose of housing the hand wheel and preventing access thereto, and likewise avoiding tampering with the valve by an unauthorized person.

It is to be noted that the openings for the reception of the pipe line are formed in opposite sides of the housing, and obviously when the housing is applied to a spigot, or to a globe valve or the like, so that the housing may engage the casing of the valve immediately below the stuffing box, one of said openings is left open. However the opening is not sufficient to permit access to the hand wheel for the purpose of operating the same. Under conditions of this kind the housing may have only one opening to avoid insertion of an instrument to operate the valve. Though the openings are formed in opposite sides of the housing, it is possible to construct a housing with an opening in one side, so as to permit said opening to engage about the casing of a valve below the stuffing box. In this case the housing will be specially constructed, while other housings may be constructed with openings in opposite sides, in which case this latter housing can be used in connection with pipe lines wherein the valve is entirely surrounded by the housing, or in connection with pipe lines wherein the housing may be connected to the valve casing immediately below the stuffing box, for the purpose of housing the hand wheel alone, instead of including the valve casing.

The hingedly supported sections adjacent where they are hingedly mounted upon the base section having abutment edges 19, which engage opposed sides of the base section to limit the hingedly supported sections in open positions, said hingedly supported sections extending laterally and upwardly.

The invention having been set forth, what is claimed is:—

1. A locked housing for pipe line valves comprising a base section which is adapted to engage under the valve, and two opposed hingedly supported sections mounted upon the base section and adapted to move in engagement with each other and assume positions over the pipe line valve, said hingedly supported sections adapted to move to positions laterally and upwardly, and means for locking the two hingedly supported sections together.

2. In a locked housing for pipe line valves, a base section, a pair of opposed hingedly supported sections mounted upon the base sections and adapted to move to positions extending laterally and upwardly, and means for locking the two hingedly supported sections.

3. In a locked housing for pipe line valves, a base section, a pair of opposed hingedly supported sections mounted upon the base section and adapted to move to positions extending laterally and upwardly, and means for locking the two hingedly supported sections, each hingedly supported section being constructed from a single piece of sheet metal comprising three sides and a top end, one side having flanges overlying and being riveted to the other two sides.
4. In a locked housing for pipe line valves, a base section, a pair of opposed hingedly supported sections mounted upon the base section and adapted to move to positions extending laterally and upwardly, and means for locking the two hingedly supported sections, each hingedly supported section being constructed from a single piece of sheet metal comprising three sides and a top end, one side having flanges overlying and being riveted to the other two sides, said flanges being extended at the hinged end of the section, and means for pivotally riveting the extensions of the flanges to the base section.
5. In a locked housing for pipe line valves, a base section, a pair of opposed hingedly supported sections mounted upon the base section and adapted to move to positions extending laterally and upwardly, and means for locking the two hingedly supported sections, each hingedly supported section being constructed from a single piece of sheet metal comprising three sides and a top end, one side having flanges overlying and being riveted to the other two sides, said flanges being extended at the hinged end of the section, and means for pivotally riveting the extensions of the flanges to the base section, the lower edge of the side having the flanges abutting one of the sides of the base section, to limit the hingedly supported section in an open position.
6. In a locked housing for pipe line valves, comprising a base section being constructed from a single piece of sheet metal having a bottom, side pieces and end pieces, the side pieces having extension flanges overlying and secured to the end pieces, opposed hingedly supported sections mounted upon the base section, each constructed from a single piece of sheet metal comprising three sides and a top end, and means carried by one of the sides for overlying and being secured to the other sides of the hingedly supported section to insure a rigid structure, said means being hingedly connected to the base section, opposed sides of the housing having openings adapted to engage with a pipe line, and thereby enclose a valve and its hand wheel, and means for locking the two hingedly supported sections together.
7. A locked housing for the hand wheel of a pipe line valve, comprising a base section, two hingedly supported sections mounted upon the base section, one of the sides of the housing having an opening to surround the casing immediately below the stuffing box of the valve, whereby the hand wheel may be inclosed in the housing, and means for locking the two hingedly supported sections together, the hingedly supported sections having abutment edges adjacent their hinged mountings to contact with the opposed sides of the base section to limit the hingedly supported sections in open positions.

In testimony whereof I hereunto affix my signature.

JAMES W. MOORE.
